UNITED STATES PATENT OFFICE.

WILLIAM F. McCUALEY, OF ELKINS, WEST VIRGINIA.

COMPOUND TOOL.

1,171,965.

Specification of Letters Patent. Patented Feb. 15, 1916.

Application filed June 3, 1915. Serial No. 31,944.

To all whom it may concern:

Be it known that I, WILLIAM F. McCUALEY, a citizen of the United States, residing at Elkins, in the county of Randolph and State of West Virginia, have invented certain new and useful Improvements in Compound Tools, of which the following is a specification.

This invention relates to a compound tool 10 of the pincer type and the principal object of the invention is to provide a tool of the character described so constructed that a bit may be grasped between the jaws of a pair of pliers and the handles of the 15 pliers releasably connected to firmly hold the jaws of the pliers in engagement with the head of the bit.

Another object of the invention is to so construct the head of the bit that when gripped by the plier jaws the bit will be prevented from having longitudinal or transverse movement.

This invention is illustrated in the accompanying drawings, wherein:—

25 Figure 1 is a view in elevation showing the bit engaged by the pliers and the handles of the pliers connected by the latch. Fig. 2 is a longitudinal sectional view taken along the line 2—2 of Fig. 3. Fig. 3 30 is a view similar to Fig. 1 but taken at right angles thereto. Fig. 4 is a transverse sectional view taken along the line 4—4 of Fig. 1. Fig. 5 is a longitudinal sectional view through the handles and latch taken 35 along the line 5—5 of Fig. 3. Fig. 6 is a sectional view taken along the line 6—6 of Fig. 5. Fig. 7 is a perspective view of a modified form of bit. Fig. 8 is a perspective view of still another modified form 40 of bit.

The pliers or wire cutters as they are sometimees called are provided with the jaws 10 and 11 which are carried by the handles 12 and 13 pivotally connected at 45 the joint 14 by means of the pivot pin 15. These jaws 10 and 11 will be provided with the usual cut-out 16 forming the wire receiving pocket and also provided with the abutment shoulders 17. It should be further noted that the pliers are provided with the usual cutters 18 and have the sides of the jaws cut away to provide the abutment shoulders 19.

50 The bit 20 may be any suitable tool such as a screw driver, punch, spindle or drill and is provided with a head 21 to be tightly

gripped between the jaws of the pliers. In one form such as shown in Figs. 1, 2 and 3 the head will be provided with a transversely extending groove forming a seat 22 positioned opposite the flanges 23. It will thus be seen that when the head of the bit is engaged by the jaws 10 and 11 the jaw 10 will fit into the seat 22 and the jaw 11 will fit between the flanges 23. 65 Therefore the jaw 10 will prevent the bit from moving longitudinally and the jaw 11 will prevent it from moving transversely. This arrangement will also prevent the bit from moving pivotally and therefore the bit 70 cannot get out of place when engaged by the jaws.

In Fig. 8 there is shown a form somewhat similar to the form shown in Figs. 1 and 2 but in this form the seat 22 is done 75 away with and a flange 24 provided between the flanges 23. Therefore the jaw 11 will fit between the flanges 23 and 24 with the flange 24 engaging the abutment shoulders 17 and the flanges 23 engaging the abut- 80 ment shoulders 19. It should be noted that in each form the flanges 23 engage the shoulders 19 to assist in preventing longitudinal movement. It should be further noted that it is immaterial whether the bit is put in 85 place with the jaw 11 between the flanges 23 or with the jaw 10 between the flanges. In Fig. 7 there has been shown another modification in which the head is constructed somewhat similar to the form shown in Figs. 1 90 and 2 but the seat 22 is omitted, the roughened gripping faces of the jaws 10 and 11 being depended upon to prevent the bit from moving outwardly and the flanges 23 engaging the abutment shoulders 19 to prevent the 95 bit from slipping inwardly when pressure is applied.

The latch 25 is provided with hinge ears 26 which are pivotally connected with the hinge ear 27 of the handle 12 by means of 100 the pin 28. The free end of the latch is provided with a socket 29 to receive the hook 30 of the handle 13 thereby permitting the handle 13 to be releasably connected with the handle 12.

105 It should be noted that the pliers are formed of resilient material such for instance as forged steel and therefore the handles will have a spring action causing a binding engagement between the hook 30 110 and latch 25. It is necessary to compress the handles slightly in order to engage the

latch with the hook and therefore when the pliers are in use as a handle for the bit the latch will not slip out of position and release the handles.

5 When this device is in use the bit is put in place between the jaws and the jaws then moved into tight engagement with the head of the bit by pressing upon the handles 12 and 13. The latch will then be moved into 10 engagement with the hook and the bit will be securely held in place. When it is no longer desired to use the bit the latch will be released and the bit removed and the pliers can then be used as ordinary wire cutters or pincers. When used as a wire cutter the latch will be swung to the dotted line position shown in Fig. 5 and will be yieldably held in this position by means of the pin 31 which is slidably mounted in 15 an opening formed in one of the hinged ears 26 and held in binding engagement with the

hinged ear 27 by means of the spring washer 32. It should also be noted that small recesses can be formed in the hinged ear 27 to receive the inner end of the pin 31 as 25 shown in Fig. 6.

What is claimed is:—

A tool adapted to be held between plier jaws, said tool having a shank provided with side flanges for engagement with the side 30 of a plier jaw and having an abutment to the rear of the flanges for engagement with the rear edge of a plier jaw whereby the tool will be held against longitudinal and transverse displacement between the plier jaws. 35

In testimony whereof I affix my signature in presence of two witnesses.

WILLIAM F. McCUALEY.
